UNITED STATES PATENT OFFICE.

JOHN MILLER RALSTON, OF BARRHEAD, SCOTLAND.

NUT TAPPING OR SCREWING MACHINE.

No. 821,376.

Specification of Letters Patent.

Patented May 22, 1906.

Application filed July 25, 1905. Serial No. 271,150.

To all whom it may concern:

Be it known that I, JOHN MILLER RALSTON, a subject of the King of Great Britain and Ireland, residing in Barrhead, Scotland, have invented certain new and useful Improvements in Nut Tapping or Screwing Machines, of which the following is a specification.

This invention relates to machines for tapping or screwing nuts; and it has for its object to improve and simplify their construction.

Under this invention the tap is held by means of grippers and is revolved in a vertical position, but without vertical movement, while the nuts are not revolved, but are fed automatically to the tap, one at a time, from a vertical holder or magazine, in conjunction with which is a vertical forcer which works in guides and which is so made as to be capable of receiving and holding the nut-blank in position and then descending, with the blank, and forcing it down and over the screwed part of the tap, whereupon the forcer rises again in readiness to receive and tap another nut-blank.

In order that my invention may be properly understood, I have hereunto appended explanatory drawings, whereon—

Figure 1 is a front view of the machine. Fig. 2 is a transverse vertical section of the machine, taken on the line $x-x$, Fig. 1. Fig. 3 is a back view of the machine. Fig. 4 is a plan of Fig. 1. Fig. 5 is a horizontal section on the line $y-y$, Fig. 2. Figs. 6, 7, and 8 are detail views. Fig. 9 is an enlarged sectional view of the grip mechanism. Fig. 10 shows a modification of the mechanism for operating the racks 7 and the slide 12. Fig. 11 is an enlarged view of the clutch-operating mechanism.

On the drawings the same reference characters wherever repeated indicate the same parts.

The machine consists of a rectangular box or frame a , supported on uprights d and within which is a bearing-socket b , which carries the tapping mechanism c . This mechanism consists of a bevel gear-wheel e , which is driven from the bevel-wheel f on a main shaft g , carried in brackets i , suitably secured to the outside of the box a , by means of the intermediate bevel-gearing h , mounted on a short shaft h' , which projects outside the box or frame a . The main shaft is driven by the pulley j from a motor, engine, or overhead

shafting. The bevel-wheel e , which is supported by means of a cylindrical bush k , which rests upon and revolves on ball-bearings l inside the cylindrical socket b , has fixed to its upper side a cylindrical frame m , which revolves along with the wheel e .

Arranged to revolve along with the cylindrical frame m are two vertically-disposed sliding plates q , carrying a ring r at their upper ends, upon which a disk s rests and is held in place by a narrow ring t , fixed to the top of the sliding plates. Secured to the disk s are two links u , connected to rocking levers v , fulcrumed on the bar 29, carried by the brackets 29^a. One of the levers v is connected by a link 28 to a cam-frame w , pivoted on bar 27^a and which is actuated by a cam w on a secondary shaft l , which latter is carried in brackets 8, secured to the outside of the box or frame a , and is driven from the main shaft g by the pulleys 8^a and belt 8^b. The vertically-reciprocating disk s has a central opening and works on a guide-cylinder s' , which is secured to the box a . The bevel-wheel e , bush k , and socket b are made with a central opening or passage-way, n , through which the nuts fall after being tapped onto an inclined chute o , made in one with the bearing-socket b , and thereafter they pass to a collecting box or receiver p .

Secured to the cylindrical frame m are two sets of guides—a top set 2 and a bottom set 2^a. (See also Fig. 9.) The two pairs of grips 3, 3^a, for holding the tap in a vertical position, work (in opposite directions) inside each set 9^a of guides. The grips 3, 3^a are opened and closed upon the tap 4 by means of segments 5, carried on spindles 6, secured in the cylindrical frame m and which engage with racks 7, 7 on the sliding plates q , q' . As will be seen clearly at Fig. 9, the segments have toes 3^b, 3^c, which engage with notches in the grips. The upper grips 3, 3^a are moved inward, so as to grasp the tap 4 by means of the simultaneous action of springs 6^a, 6^b, (see Fig. 9,) while the grips 3^a, 3^c are likewise caused to grip the tap by the action of springs 4^a, 4^b. When the upper grips 3, 3^a engage the tap, they are held positively in the engaged position by means of locking-bars q' , q'' , which are pivoted at q^2 , q^2 . When the racks descend, the bars, which pass through slots q^3 in the rack-plates, are forced down by said plates out of engagement with the grips, while when the racks rise they are lifted up, so as to engage the

projections q^4 q^4 on the grips. The upper pair of grips and the lower pair of grips are alternately moved out of engagement with the tap by the action of the toes 3^b 3^c of the segments, which engage with the notches and pull back the grips (against the action of the springs) out of contact with the tap.

Formed in one with the guide-ring s' is a narrow table 9, to which is bolted or otherwise secured a magazine or hopper 10 for holding the nuts 11 to be tapped. Working in a slot at the bottom of this magazine or hopper 10 is a sliding plate 12, (see also plan view, Fig. 8,) whose inner end 13 is made somewhat V-shaped to fit two adjacent sides of a nut, while to its outer end 14 is attached a rod 15, which passes through a hole 16 in an extension 17 of the frame or box a . The sliding plate 12 with rod 15 is reciprocated by the action of the spring 20, which thrusts it forward, and by a bell-crank lever 19, pivoted at 19^a to the magazine 10, which pulls it back. When necessary—say, for instance, when starting the machine—the plate can be pulled back by the handle 21.

Guided by a hole 22 in an arm 23, secured to the magazine, is a hollow or tubular forcer 24, which is expanded at its lower end and is made with a recess or enlargement open at one side and which is of hexagon or other suitable shape at the interior, so as to snugly receive and hold a nut, as shown at Fig. 8, when it is delivered to it by the slide 12. This forcer when a nut is being tapped exerts a downward pressure on the nut (by means of a spring 25, wound round the forcer 24 and bearing against the arm 23 and a ring 26 on the forcer 24) and carries it down and over the screwed part of the tap. The forcer 24 works inside of and is pinned to the fork of a lever 27, (see also Fig. 6,) pivoted on the bar 27^a , (carried by the brackets 29^a .) This lever 27 is caused to lift up the forcer after each downward movement under the action of the spring 25 by means of the lever 38, acted on by the cam 34. As will be seen, 38 has a screw 33, which bears against the under side of the lever 27. The forcer is guided at its upper end by the hole in the arm 22 and at its lower end by beads 24^a in the guide-cylinder s' , which engage with vertical grooves in the forcer.

Pins 30 are fixed into the outer ends of the rocking levers $v v$ and bear against the arms 31 of the double bell-crank lever 19, fulcrumed at 19^a . This lever has a single central arm 18, which engages with a slot 32 (see Fig. 8) at the outer end of the sliding plate 12.

A cam projection 35 on the clutch part 36 actuates a toggle-joint 39 by means of the roller 40, carried by the toggle-link 41, which latter is pivoted to the lever 38 a , the upper end of which is forked, so as to embrace the part 42 of the clutch, while the lower end is fulcrumed at 43 and is provided with a crank-

arm 47, having a weight 47 a . The part 42 of the clutch is automatically put into engagement with the part 36 by the action of the weight 47 a and is thrown out of engagement at the proper times by the action of the cam projection 35 on the toggle-joint 39. The part 42 can be held out of engagement for a certain period by means of a rocker 44, pivoted at 44^a , and which when held in the horizontal position under the action of a spring 46 engages a detent 44 b on the lever 38 a . The rocker can be thrown out of engagement with the detent by the raising of the rod 45, secured to the rocker and to the lever 38. When the clutch is in gear, the cams 34 35 on the clutch part 36 and the cam w on the sleeve extension 37 of the clutch part are all put in action. The clutch part 36 and sleeve 37 are loose on the shaft l .

The action of the machine is as follows: 85 The magazine 10 is filled with nut-blanks and the machine started, and thereafter the nut-blanks are started to feed by pulling back the handle 21, so as to allow the first blank to fall down onto the table 9. When this is done, 90 the spring 20 acts on the slide 12 and causes it to place the nut-blank on top of the tap 4 and in the enlargement at the lower end of the forcer 24, whereupon the latter presses down the nut by the action of the spring 25 95 and forces it down and over the screwed part of the revolving tap 4. The forcer 24 follows the nut down the tap, and when the nut is off or clear of the screwed part at the bottom of the tap the forcer is allowed to drop, 100 and so, by means of rod 45, which is attached to the lever 38, causes the rocker 44 to disengage the lever 38 a , and so operates the cams w 34 35. During the time the clutch 42 36 makes one revolution the cams w 34 35 operate the levers v 27 38, and the levers v force down the disk s and plates q q with racks 7. As the plates q drop they release the pivoted bars q' , which allow the top grips 3 to be opened laterally by the action of the segments 5. When the racks 7 drop, they cause the segments 5 to close the lower grips 3^a 3^a and open the top grips 3 3 , thus allowing the tapped nut to fall from the top to the bottom grips, and at the same time the levers v 115 move the bell-crank 19 and allow a second nut to fall onto the table 9. On the upward stroke of levers v the motions are reversed, so as to close the upper grips and open the bottom grips, thereby allowing the tapped nut to fall down the passage n into the receiver p . During this same revolution the forcer 24 has been lifted by the action of cam 34 on levers 38 and 27, and when the forcer is up clear of the tap another nut-blank from the magazine 120 is fed or placed onto the top of the tap and held in position by the forcer, and the cycle of operations is completed by the clutch 42 36, being put out of gear by means of cam 35. The clutch is kept out of gear until the forcer 130

again descends and brings the clutch 42 again into action, as before. Lubricant for the tap is supplied to the top of the tubular forcer and runs down same.

5 During the time that the cycle of operations as described is being carried out the tap continues to revolve in the one direction, as there is always one of the pairs of grips holding the tap, the one pair being on before the other is 10 off. The bottom grips instead of being tightly held onto the tap by means of levers q are held in action by the springs 4^a 4^b, the tap being held by the top grips when tapping or screwing the nut, the bottom grips only 15 steadying the tap to allow of the nut being cleared of the top grips.

A modification of the mechanism for operating the racks 7 and the slide 12 is shown at Fig. 10. In this case the cam-frame w' is 20 provided with a downward extension w^3 and is pivoted at w^4 in the brackets w^5 , secured in the box a . The extension has a pin w^6 , which works in the slot w^7 of the lever w^8 , which is forked and is fulcrumed to the box 25 a at w^9 . Each prong of the fork is connected by a joint w^{10} to the disk ring t . It will be readily seen that as the cam w revolves it oscillates the extension w^3 and lever w^8 , and so raises and lowers the disk s , plates 30 q q , and racks 7 7. The cam 34 operates the lever 38, fulcrumed on the bracket w^5 at 29, which is in this case pin-jointed at 38^b to the forcer 24. The slide 12 is operated by lever 19, which latter has a rod 19^b jointed to it 35 and also connected to the extreme end of the lever w^8 , so that the movements of said lever w^8 are communicated to the slide 12, with the result that the latter is positively reciprocated.

40 Having now particularly described and ascertained the nature of my said invention and in what manner the same is to be performed, I declare that what I claim is—

1. The combination of tap-holding grip- 45 per mechanism comprising two sets of grips slidable toward and from the tap position, means for alternately drawing the sets of grips out of the tap-holding position and comprising oscillatory members each for em- 50 gaging a grip from one set on one excursion and a grip from the other set on the return excursion, segments carried by the respective oscillatory members, racks engaging the segments, and means for reciprocating the 55 racks.

2. The combination of a frame, means for revolving the same, a plurality of sets of grips in the frame, racks and segments for operating the grips for alternately grasping and 60 holding a tap, means for forcing nut-blanks down and over the tap, a slide for automatically feeding the nut-blanks successively to the forcer, cams and levers for operating the forcer, the racks, and the slide, a driver for 65 said cams, clutch mechanism for connecting

the cams and driver, means controlled by the cams for throwing the clutch mechanism out of gear, and means controlled by the forcer for throwing the clutch mechanism into gear.

3. The combination with a rotatable mem- 70 ber, of two sets of tap-holding grips carried thereby, spring-pressed means for feeding blanks over the tap, cam mechanism, clutch-controlled means for actuating the cam mech- 75 anism, means controlled by the cam mech- anism for retracting the clutch after the release of the feeding means to the influence of its spring, means controlled by the cam mech- anism for retracting the feeding means and tensioning the spring thereof, and means con- 80 trolled by the feeding means on the comple- tion of its feeding movement for throwing the clutch into operative position.

4. The combination with a rotatable mem- 85 ber, of two sets of tap-holding grips carried thereby, spring-pressed means for feeding blanks over the tap, cam mechanism, clutch- 90 controlled means for actuating the cam mech- anism, means controlled by the cam mech- anism for retracting the clutch after the release of the feeding means to the influence of its spring, means controlled by the cam mech- anism for retracting the feeding means and tensioning the spring thereof, means con- 95 trolled by the cam mechanism for presenting nut-blanks to the feeding means upon its re- 100 traction, and means controlled by the feed- ing means on the completion of its feeding movement for throwing the clutch into op- erative position.

5. In a nut-tapping machine, the combina- 105 tion with a rotatable member, of two sets of tap-holding grips carried thereby, means for closing the grips, an oscillatory member hav- 110 ing means for engaging the grips of the re- spective sets and upon its oscillation in one direction retracting a grip of one set and upon its return retracting a grip of the other set, a sector carried by said oscillatory member, a reciprocating rack in mesh therewith, and means for reciprocating said rack.

6. In a nut-tapping machine, the combina- 115 tion with a rotatable member, of two sets of tap-holding grips carried thereby, means for closing the grips, an oscillatory member hav- 120 ing means for engaging the grips of the re- spective sets and upon its oscillation in one direction retracting a grip of one set and upon its return retracting a grip of the other set, a sector carried by said oscillatory member, a reciprocating rack in mesh therewith, means for reciprocating said rack, means for locking one set of grips, and means carried by the 125 racks for controlling said locking means.

7. In a nut-tapping machine, the combina- 130 tion with a rotary frame, of two sets of tap- holding grips carried thereby, means for clos- ing the grips, an oscillatory member having means for engaging the grips of the respec- tive sets and upon its oscillation in one direc-

tion retracting a grip in one set and upon its return retracting the grip in the other set, a toothed sector carried by said oscillatory member, a slide mounted on said frame for reciprocation axially thereof, a rack carried by the slide and in mesh with said sector, a ring held from rotation and engaging the slides, cam mechanism for reciprocating said ring axially of the frame, means for locking

one set of grips in their closed position, and to said slide provided with means for controlling said locking means.

Signed this 14th day of July, 1905, in the presence of the two undersigned witnesses.

JOHN MILLER RALSTON.
